TELEPHONE SHOULDER REST

Eddie S. Scarlett, South Pasadena, Calif.

Application November 23, 1946, Serial No. 711,887

1 Claim. (Cl. 179—157)

1

This invention relates to a device for use with a telephone hand set of the type commonly employed with the so-called "French" type telephone.

The hand set employed with such telephones includes a mouthpiece and an earpiece mounted on a common handle member which is designed to provide a convenient grip for the user's hand. A disadvantage of this arrangement is that it requires the use of one hand to maintain the hand set in operative relation with respect to the ear and mouth of the user, and thereby leaving only one hand free for other work, such as taking notes, writing memorandums, etc.

In business and professional activities, it is well known that certain occasions require that the telephone hand set be maintained in position by the user for long periods of time while waiting for information or while waiting for the desired telephone connection. In order to avoid the necessity of holding the hand set in position manually (which action may produce unnecessary fatigue of the user) various attempts have been made toward providing an attachment for the hand set which would enable the telephone user to maintain the device in position without requiring the use of one of his hands. For the most part these attempts have met with failure since the type of device employed for accomplishing this purpose was either too cumbersome or bulky or interfered with repositioning of the hand set within the cradle provided on the stationary part of the telephone assembly.

Accordingly, it is the principal object of my invention to provide an attachment for a telephone hand set which will enable a user to maintain the hand set in operative position without requiring the use of either of his hands.

Another object is to provide a removable device for attachment to the handle portion of a telephone hand set, which device is provided with an outwardly projecting horn adapted to engage the shoulder of the telephone user and thereby enable the user to maintain the earpiece and mouthpiece in operative position without requiring the use of one of his hands.

Another object is to provide such an attachment for a telephone hand set which is designed in a manner to avoid interference with normal positioning of the hand set on the stationary cradle of the telephone.

A further object is to provide such a removable device having a horn provided with an extension which may be brought into operative position or held in a retracted position when desired.

2

Other objects and advantages relate to details of construction and mounting of the device in position on a conventional type of telephone hand set.

5 In the drawings:

Figure 1 is a perspective view illustrating the preferred embodiment of my invention in position on the shoulder of a telephone user;

Figure 2 is a perspective view showing a conventional French-type telephone having a hand set on which my attachment is mounted;

Figure 3 is a side elevation of a telephone hand set showing details of mounting of the attachment embodying my invention;

15 Figure 4 is an end view of the device shown in Figure 3;

Figure 5 is an enlarged perspective view showing details of construction of the attachment embodying my invention; and

20 Figure 6 is a view showing a modification thereof.

Referring to the drawings, the telephone base generally indicated at 10 is provided with spaced projections 11 and 12 forming one side of the cradle which supports the hand set 13 in its inoperative position. Duplicate projections are provided on the opposite side of the cradle and the hand set 13 is adapted to rest between them, as will be readily understood. The bulbous earpiece 14 on one end of the hand set is connected by means of the central handle portion 15 to the mouthpiece 16 provided on the other end of the hand set.

The support attachment generally designated at 17 encircles a portion of the handle 15 and extends from a position midway of the handle toward the earpiece 14. An outwardly extending horn 18 is provided on the device 17 which extends in a direction away from the earpiece 14. This horn 18 is adapted to hook over the shoulder of the user in a manner to prevent the hand set from sliding away from operative position when the telephone user releases his grip from the handle 15. The curved outer edge of the horn is provided with a surface which affords a relatively high coefficient of friction as is well known in the art. Such a surface is indicated by the crossed lines in Figures 1, 2 and 5 of the drawing.

The attachment device 17 may be made of any 50 convenient or desirable material or composition and may be split longitudinally as indicated at 19 if desired. I have found that a plastic composition, such as polystyrene, is well suited for this use.

55 A forward end 20 is contoured to provide a

socket fitting snugly against the exterior surface of the earpiece 14 and the rearward portion 21 is curved to match the exterior surface of the handle 15. An open slot 22 is provided between the downwardly extending fingers 23 at the rearward end of the attachment 17. If the split construction is not employed and the device formed integrally of a single piece of material, the fingers 23 should be resilient to permit separation therefrom in a direction to widen the slot 22 for the purpose of installing the device 17 on the handle 15. In position the fingers 23 spring back toward the handle to anchor the device 17 in position and prevent sliding movement longitudinally of the handle. The contoured end 20 which fits snugly against the earpiece 14 prevents rotary movement about the axis of the handle 15. If a split construction is employed with a dividing line, as indicated at 19, a set screw 24 may be employed for holding the two halves in assembled relation, and in such event the fingers 23 need not be of resilient construction.

An important feature in the construction of the attachment device 17 for adapting it to fit snugly on conventional telephone hand sets is the provision of the webs 25 which extend under the curved portion 26 at the earpiece and of the handle 15. These webs 25 cooperate with the flange 27 formed at the extreme forward end of the attachment fitting 17 to further resist any relative motion between the attachment 17 and the hand set 13.

The material employed at the rearward end 21 of the attachment fitting 17 is sufficiently thin to enable the entire device, when assembled on the hand set 13, to fit easily within the cradle provided between the pairs of upstanding projections 11 and 12. The device 17 therefore when once installed on the hand set 13 remains in fixed position relative thereto and need not be locked or turned or disconnected when the hand set 13 is replaced on the telephone base 10. Furthermore, the device 17 does not interfere with normal use of the hand set 13 in the event that the telephone user elects to hold it manually in the conventional fashion.

In the modification shown in Figure 6, a spring wire 30 formed in the shape of a U is bent somewhat at 31 and extends inwardly at 32 into a recess 33 provided in the horn 18a. Shallow grooves 34 extend outwardly from the recess 33 and the portions 35 of the spring wire 30 between the recess 33 and the bend 31 are adapted to be

received in the groove 34 when the wire is pivoted upwardly about the recess 33 into the dotted line position shown in Figure 6. The resilience of the wire maintains the portions 35 and grooves 34 in operative position against accidental displacement. This wire provides, in effect, an extension for the horn 18a in the event that such extension should be necessary or desirable for use by a particular person or persons. The spring wire 30 may be pivoted to its inoperative position as shown by the full lines in Figure 6 and in this position it is out of the way and inconspicuous.

Having fully described my invention, it is to be understood that I do not wish to be limited to the details herein set forth, but my invention is of the full scope of the appended claim.

I claim:

An attachment for a telephone hand set of the type having an earpiece and a mouthpiece mounted at opposite ends of a common handle, said attachment comprising a body having first resilient gripping elements located to embrace and clamp a portion of the handle therebetween, a horn on said body providing a shoulder support for the telephone user, said horn extending in a direction rearwardly away from the earpiece of the telephone hand set and being shaped to provide a curved outer edge to conform to and hook over the shoulder of the user, the said curved outer edge being provided with a surface presenting a relatively high coefficient of friction, a socket portion on said body shaped to conform to and contact the rear surface of said earpiece whereby relative rotational movement between said body and said handle is prevented and additional gripping elements on the socket portion adjacent said first resilient elements located to cooperate with and clamp the external surface of the earpiece adjacent its juncture with said handle whereby relative longitudinal movement between said body and said handle is prevented.
